UNITED STATES PATENT OFFICE.

REUBEN W. PERRY, OF SPENCER, MASSACHUSETTS.

SHARPENING DEVICE.

1,252,612.

Specification of Letters Patent.

Patented Jan. 8, 1918.

Application filed June 4, 1917. Serial No. 172,596.

To all whom it may concern:

Be it known that I, REUBEN W. PERRY, a citizen of the United States, residing at Spencer, in the county of Worcester and 5 State of Massachusetts, have invented new and useful Improvements in Sharpening Devices, of which the following is a specification.

One object of this invention is to provide, 10 as a member of a sharpening device, a bed adapted to rest on a table or other support, and provided with means for guiding a manually movable abrasive body or sharpener, such as a stick of solidified agglutinated car- 15 borundum or a stick of natural stone, in a predetermined path, and with means for supporting a blade having beveled edge-forming portions, with either of said edge-forming portions in the path of movement of the 20 acting face of the sharpener, to the end that an unskilled operator may maintain and preserve the proper bevel of said faces in sharpening the blade.

Another object of the invention is to enable said bed to hold a scissors or shear blade with its edge face in the path of movement of the acting face of the sharpener, so that the bed may be used either as a member of a knife-sharpener or of a scissors-sharpener. 25 30 To these and other related ends the invention consists in the improvements which I will now proceed to describe and claim.

Of the accompanying drawings forming a part of this specification,—

35 Figure 1 is a perspective view of a bed constituting a member of a sharpening device embodying the invention.

Fig. 2 is a perspective view of a sharpener constituting another member of the sharpen- 40 ing device.

Fig. 3 is an edge view of the bed and a transverse section of a knife blade supported thereby, another blade being shown by dotted lines.

45 Fig. 4 is a view similar to Fig. 3, illustrating the function of the bed in holding a scissors blade.

Figs. 5 and 6 are edge views illustrating a modification.

50 The same reference characters indicate the same parts in all of the figures.

The bed member of my improved sharpening device is preferably of the general form represented by Fig. 1, and may be made of 55 wood or other suitable material, the bed be-

ing adapted to rest on a table or other support.

A part of the upper side of the bed constitutes a flat sharpener-guiding face 12, on which the flat acting face 13 of a sharpener 14 may be manually reciprocated. The bed is provided with two blade-supporting faces 15 and 16, each of which is inclined relatively to the guiding-face 12 and to the other supporting face. Said faces 15 and 16 meet 60 to form an obtuse angle, which is preferably in or slightly below the plane of the sharpener-guiding face 12.

Each of the faces 15 and 16 is adapted to support a knife blade 17 having two beveled edge-forming portions 17^a, with one of said portions substantially in the plane of the guiding-face 12 and in the path of the acting-face of the sharpener 14, as indicated by full and dotted lines in Fig. 3, the blade 75 being first supported by one of the supporting faces, with one of its portions 17^a uppermost, and then by the other supporting face, with its opposite portion 17^a uppermost. The inclination of the supporting faces 15 80 and 16 relatively to the guiding face 12 insures the preservation of the proper bevel of the blade portions 17^a during the sharpening operation, and enables the blade to be accurately sharpened by an unskilled operator. 85

I prefer to provide means for confining the blade against displacement by the sharpener. As shown by Figs. 1 and 3, I have embodied the confining means in a corrugated 90 plate 19 attached to one edge of the bed, the corrugations of said plate forming a plurality of sockets 20, and a stop member such as a pin 21, adapted to be inserted in either of said sockets and to bear against the back 95 of the blade 17 resting on the face 16. The acting stroke of the sharpener 14 is usually in the direction indicated by the arrow in Fig. 3, so that the displacement of the blade by movement of the sharpener in the direction indicated, is prevented by the stop member 21. The blade resting on the face 15 is not liable to displacement in the direction indicated; hence in Figs. 1 and 4 I have shown blade-confining means adapted to co- 100 operate only with a blade resting on the face 16. It is obvious, however, that additional blade-confining means may be provided as shown by Fig. 3, adapted to co-operate with a blade resting on the face 15. 105 110

To enable the bed to hold a scissors or shear blade 22 with its edge face 22^a in the path of the acting face of the sharpener 14, as indicated by Fig. 4, I make the bed 5 in two separable sections 23 and 24, the section 23 being called the body section, and the section 24 the movable section. The faces 12 and 15 are formed on the body section 23, and the face 16 is formed on the 10 movable section 24. Said sections are provided respectively with clamping faces 25 and 26, which are abutted together, as shown by Figs. 1 and 3, when the bed is used to support a knife blade, and are separated, 15 as shown by Fig. 4, to admit a scissors blade 22 between them, as shown by Fig. 4. The said clamping faces are inclined and hold the relatively wide sides of the blade 22 correspondingly inclined, the edge face 22^a being in substantially the same plane as the 20 sharpener guiding face 12.

I have provided clamping means for separably connecting the sections 23 and 24, said means being preferably embodied in a bent rod composed of a longer arm 27 and shorter arm 28, and a neck 29 connecting said arms. The neck 29 is seated on the movable section 30 and the longer arm 27 extends through the sections 23 and 24 and is screw-threaded at one end and provided with a clamping nut 30 seated on the body section 23. The shorter arm 28 extends through the section 24 and into, but not wholly through, the section 23, the function of said 35 shorter arm being to prevent the section 24 from turning on the longer arm 27. When the nut 30 is turned outwardly it permits the separation of the clamping faces 25 and 26 and the interposition of a blade 22 between them.

Figs. 5 and 6 show a modified form of bed adapted to confine a blade 17 in either of the two positions shown by said figures. In said modification the bed includes four 45 sections 31, 32, 33 and 34, these sections being separably connected by means such as the bent rod composed of the arms 27 and 28, and the neck 29, and the clamping nut 30. The sections 32 and 33 are provided respectively with inclined blade-supporting faces 35 and 36, and the sections 31 and 34 are provided respectively with sharpener guiding faces 37 and 38, and with inclined clamping faces 39 and 40, adapted to 55 coöperate with the faces 35 and 36 in clamping the blade 17.

As shown by Fig. 2, the sharpener is provided with a hand-grip portion offset from its acting face, a part of said hand-grip portion being preferably utilized as a sharpener. 60 In other words, the member shown by Fig. 2 includes two sharpeners 14 and 14^a, which may be alike in form, but of different grain or texture, one being coarser than the other, 65 each sharpener having a flat acting face 13.

The two sharpeners are connected by a neck 41, preferably of wood, glued to the sharpeners. It will now be seen that either of the sharpeners and the neck constitute a handle or hand-grip which is offset from the acting face of the other sharpener, so that the fingers of the operator are not liable to come in contact with a knife blade supported by the bed.

I claim:

1. A bed constituting a sharpening-device member, having a sharpener-guiding face, and two blade-supporting faces, each inclined relatively to said guiding face and to the other supporting face, the relative arrangement of said faces being such that a blade may be supported by either inclined face with one of its beveled edge-forming portions in the plane of said guiding face and in the path of a sharpener guided thereby.

2. A bed constituting a sharpening-device member having a sharpener-guiding face and a blade-supporting face inclined relatively to said guiding-face, the relative arrangement of said faces being such that a blade may be supported by said inclined face with one of its beveled edge-forming portions in the plane of said guiding face.

3. A bed constituting a sharpening-device member having a sharpener-guiding face and a blade-supporting face inclined relatively to said guiding-face, the relative arrangement of said faces being such that a blade may be supported by said inclined face with one of its beveled edge-forming portions in the plane of said guiding-face, said bed being provided with a stop member adapted to bear on the back of the blade and confine the latter against displacement by the sharpener.

4. A bed as specified by claim 1, provided with a plurality of sockets and with a stop member engageable with either of said sockets, said stop member and sockets constituting means for confining a blade against displacement by the sharpener.

5. A bed as specified by claim 1, comprising a body section having the said sharpener-guiding face and one of the said inclined faces, a movable section having the other inclined face, said sections being provided with opposed inclined clamping faces adapted to hold a shear or scissors blade with its edge face in the plane of said guiding face, and clamping means for separably connecting said sections.

6. A bed as specified by claim 1, comprising a body section having the said sharpener-guiding face and one of the said inclined faces, a movable section having the other inclined face, said sections being provided with opposed inclined clamping faces adapted to hold a shear or scissors blade with its edge face in the plane of said guiding face.

face, and a bent rod composed of a longer and a shorter arm and a neck connecting said arms and seated on the movable section, said longer arm extending through both sections and having a clamping nut seated on the body section, while the shorter arm extends through the movable section and partly

into the body section and constitutes a steady pin, preventing turning movements of the movable section on the longer arm. 15

In testimony whereof I have affixed my signature.

REUBEN W. PERRY.
